UNITED STATES PATENT OFFICE.

ERUCHSHAW BYRAMJI DAROOWALLA, OF BOMBAY, INDIA.

LOCK.

1,272,230.

Specification of Letters Patent.

Patented July 9, 1918.

Application filed February 25, 1916. Serial No. 80,431.

To all whom it may concern:

Be it known that I, ERUCHSHAW BYRAMJI DAROOWALLA, a subject of the Emperor of India, residing in Bombay, in India, have 5 invented certain new and useful Improvements in Locks, of which the following is a specification.

This invention relates to locks and provides means which render the picking of 10 locks more difficult.

The invention comprises a key, bits on the same side of the stem of the key, two distinct lever locks, and a single main lock bolt, the lever locks being operated by the bits at 15 different periods of revolution of the key and so combined that one locks the other.

In one form of the invention the lock bolts act at right angles to each other and the two tongues of the key come into action in positions 20 90 degrees apart.

The lock case may be divided by a partition into divisions wherein the two sets of lock mechanism are located.

A construction according to the invention 25 is shown on the annexed sheet of drawings, in which:

Figure 1 shows the lock with the cover removed, exposing the mechanism above the partition;

Fig. 2 the mechanism behind the partition;

Figs. 3 and 4 two views of one of the bolts;

Fig. 5 is a section of the complete lock as seen from the end where the other bolt 35 projects;

Fig. 6 a plan of the last mentioned bolt;

Fig. 7 a side view of Fig. 6;

Fig. 8 an end view of Fig. 6; and

Fig. 9 the key with the double tongue.

The casing is shown at *a* with its cover at 40 *b*. (Fig. 5) and the partition at *c*. The mechanism illustrated in Fig. 1 is acted upon by the upper bit *r*¹ of the key. In the position shown in Figs. 1 and 2 the lock is shown locked and assuming that it is a case of unlocking, the key *r* is inserted in the key hole *m* and the lever *g*, pivoted at *h*, is raised until it clears the locking pin *o* with the result that the end *n* of the bolt *f* (Figs. 3 and 4) can be moved out of the slot *t* in the extension *e* of the other bolt *d*, and rests 50 between the posts *p* and *n* in unlocked position. The key being moved through 90° further in a clockwise direction the bit *r*² then engages the lever *g*, pivoted at *i* raising it to clear the locking pin *k*¹ on the bolt *d* (Fig.

2). The bolt *d* is then moved back and the operation of unlocking the lock is complete. The reverse movement shoots the two bolts in reverse order. The lever mechanism is 60 similar in the two locks.

What I claim as my invention and desire to secure by Letters Patent is:—

1. In a lock mechanism, a key, two bits thereon, a lock casing, a single main lock bolt arranged in the casing and adapted to be projected at one end exteriorly of the same, a lever lock adapted to lock the bolt in projected position, one of the said bits being adapted to operate the said lever lock 70 to unlock the bolt and to effect the sliding movements of the latter, a second bolt adapted to engage with and lock the first bolt in projected position, a second lever lock distinct from the first and adapted to lock the 75 said second bolt when the latter is in locking engagement with the first bolt, said second lever lock being adapted to be operated by the other bit of the key to cause the said second bolt to unlock the first bolt, both of 80 the said lever locks being operable by the bits at different periods of revolution of the key.

2. In a lock mechanism, a key, two bits thereon, a lock casing, a single main lock bolt arranged in the casing and adapted to be projected at one end exteriorly of the same, a partition within the casing and dividing the interior of the latter into two compartments, a lever lock arranged in one 85 compartment and adapted to lock the bolt in projected position, one of the said bits being adapted to operate the said lever lock to unlock the bolt and to effect the sliding movements of the latter, a second bolt arranged 90 within the other compartment and adapted to engage with and lock the first bolt in projected position, a second lever lock arranged in the same compartment with the said second bolt and adapted to lock the latter when 100 it is in locking engagement with the main bolt, said second lever lock being adapted to be operated by the other bit of the key to cause the second bolt to unlock the main bolt, both of the said lever locks being operable by the bits at different periods of 105 revolution of the key.

3. In a lock mechanism, a key, two bits thereon, a lock casing, a single main lock bolt arranged in the casing and adapted to be projected at one end exteriorly of the same, a second bolt in the casing and slid-

able at right angles to the main bolt and engageable therewith to lock the latter in projected position, a lever lock adapted to engage with and lock the main bolt in projected position, a second lever lock adapted to engage with and lock the said second bolt when the latter is in locking engagement with the main bolt, one of the bits of the key being adapted at one period of revolution of the key to operate one of the lever locks to free the second bolt and to slide the latter out of engagement with the main bolt, and the other bit being adapted during a further period of revolution of the key to operate the other lever lock to cause it to unlock the main bolt and to effect the sliding movement of the latter as and for the purpose specified.

10

4. In a lock mechanism, a key, two bits thereon, a lock casing, a single main lock bolt in the casing and adapted to be projected at one end exteriorly of the same, said bolt being provided with a slot, a second bolt in the casing and slideable at right angles to the main bolt and engageable at one end in the slot of the main bolt to lock, the latter in projected position, a pivoted lever lock adapted to engage with and lock the second bolt when the latter is in locking engagement with the main bolt, a second pivoted lever lock adapted to engage with and lock the main bolt in projected position, one of the bits of the key being adapted during one period of revolution of the key to swing the first-mentioned lever lock to free the said second bolt and to slide the latter out of the slot in the main bolt, and the other bit being adapted during a further period of revolution of the key to swing the second lever lock to free the main bolt and to effect the sliding movement of the latter.

5. In a lock mechanism, a key, two bits thereon, a lock casing, a partition dividing the interior of the casing into two compartments, a main lock bolt in one compartment of the casing adapted to be projected at one end exteriorly of the same and having an extension projecting into the other compartment, said extension being provided with a slot, a second bolt arranged in the compartment into which the extension projects, and engageable within the slot of said extension to lock the main bolt in projected position, a lever lock also arranged in the last-mentioned compartment and engageable with the said second bolt to lock it when engaged in the slot, a second lever lock arranged in the other compartment of the casing and engageable with the main bolt to lock it when

in projected position, one of the bits of the key being adapted during one period of revolution of the key to operate one of the lever locks to free the said second bolt and to slide the latter out of engagement with the slot in the main bolt extension, and the other bit being adapted during a further period of revolution of the key to operate the other lever lock to cause it to unlock the main bolt and to effect the sliding movement of the latter as and for the purpose specified.

6. In a lock mechanism, a key, two bits thereon, a lock casing, a single main lock bolt arranged in the casing and adapted to be projected at one end exteriorly of the same, a pivoted lever lock adapted to lock the bolt in projected position, one of the said bits being adapted to operate the said lever lock to unlock the bolt and to effect the sliding movements of the latter, a second bolt adapted to engage with and lock the first bolt in projected position, a second pivoted lever lock distinct from the first and adapted to lock the said second bolt when the latter is in locking engagement with the first bolt, said second lever lock being adapted to be operated by the other bit of the key to cause the said second bolt to unlock the first bolt, both of the said lever locks being operable by the bits at different periods of revolution of the key.

7. In a lock mechanism, a key, two bits thereon, a lock casing, a slideable main lock bolt in the casing and adapted to be projected at one end exteriorly of the same and being provided with a locking pin, a second bolt in the casing slideable at right angles to the main bolt and provided with a locking pin, said second bolt being adapted to engage with and lock the main bolt in projected position, a lever lock provided with a lug adapted to engage with the locking pin on the second bolt to lock the latter in locking engagement with the main bolt, a second lever lock provided with a lug adapted to engage with the locking pin on the main bolt to lock the latter in projected position, the said lever locks being operable by the bits of the key during different periods of revolution of the latter for the purposes set forth.

In testimony whereof I have signed my name to this specification in the presence of two subscribing witnesses.

ERUCHSHAW BYRAMJI DAROOWALLA.
